CLAIM

The ornamental design for a tobacco pipe tool tote, as shown and described.

DESCRIPTION

This application identifies pending U.S. Patent application Ser. No. 13/317,089, as a related prior application filed by the same named inventor for the purpose of identification.

FIG. 1 is a perspective view of the tobacco pipe tool tote.

FIG. 2 is a front view of the tobacco pipe tool tote.

FIG. 3 is a rear view of the tobacco pipe tool tote.

FIG. 4 is a right side view of the tobacco pipe tool tote.

FIG. 5 is a left side view of the tobacco pipe tool tote.

FIG. 6 is a top view of the tobacco pipe tool tote; and,

FIG. 7 is a bottom view of the tobacco pipe tool tote.
